DESIGN FOR A BEACH BAG

Elizabeth N. Graham, New York, N. Y.

Application December 26, 1947, Serial No. 143,359

Term of patent 14 years

(Cl. D87—3)

To all whom it may concern:

Be it known that I, Elizabeth N. Graham, a citizen of the United States of America, residing in New York city, county of New York, and State of New York, have invented a new, original, and ornamental Design for a Beach Bag, of which the following is a specification, reference being had to the accompanying drawing, forming part thereof, wherein,

I claim:

The ornamental design for a beach bag, substantially as shown.

ELIZABETH N. GRAHAM.
